UNITED STATES PATENT OFFICE.

WILLIAM S. ESSICK, OF READING, PENNSYLVANIA.

DESIGN FOR AN OVEN-DOOR FOR RANGES.

SPECIFICATION forming part of Design No. 34,418, dated April 23, 1901.

Application filed March 29, 1901. Serial No. 53,562. Term of patent 7 years.

To all whom it may concern:

Be it known that I, WILLIAM S. ESSICK, a citizen of the United States of America, and a resident of Reading, in the county of Berks and State of Pennsylvania, have invented and produced a certain new and original Design for an Oven-Door for Ranges, of which the following is a specification.

The drawing is a front elevation of an oven-door, showing my design.

My design relates particularly to the surface ornamentation shown, the leading or material feature of which consists in the representation, in relief, upon the exposed surface, of double bow-knots *a a*, having long fancifully-twisted and bent projecting portions *b b* beyond the bow, with curved forked ends *c c*, the whole forming a graceful relief ornamentation, with the bow-knots and their

fancifully-curved projections arranged upon 20 the outer surface of the door, around the centrally-located ornamental name-plate *d*, as shown, upon which also is similar bow-knot ornamentation *e*.

It is apparent that this design is also applicable to other similar or connected surfaces.

Having described my invention, what I claim as new, and desire to secure by Letters Patent, is—

The design for an oven-door for ranges, substantially as shown and described. 30

Signed at Reading, Pennsylvania, this 23d day of March, 1901.

WM. S. ESSICK.
